(57) CLAIM

The ornamental design for a mule as shown and described.

DESCRIPTION

FIG. 1 is a front view of a mule showing my new design; FIG. 2 is a right side view thereof; FIG. 3 is a top view thereof; FIG. 4 is a left side view thereof; FIG. 5 is a perspective view thereof; FIG. 6 is a back view thereof; FIG. 7 is a bottom view thereof. FIG. 8 is a right side view of another embodiment; FIG. 9 is a top view thereof; FIG. 10 is a left side view thereof; FIG. 11 is a perspective view thereof; FIG. 12 is a back view thereof; FIG. 13 is a bottom view thereof; and, FIG. 14 is a front view thereof.

The broken lines depict portions of the mule that form no part of the claimed design.
